UNITED STATES PATENT OFFICE.

DANIEL W. CHASE, OF HAVERHILL, MASSACHUSETTS.

SANDAL.

1,012,245.

Specification of Letters Patent. Patented Dec. 19, 1911.

Application filed April 15, 1911. Serial No. 621,421.

To all whom it may concern:

Be it known that I, DANIEL W. CHASE, a citizen of the United States, residing at Bradford, Haverhill, in the county of Essex and State of Massachusetts, have invented 5 certain new and useful Improvements in Sandals; and I do hereby declare the following to be a full, clear, and exact description of the invention, such as will enable others skilled in the art to which it appertains to 10 make and use the same.

The present invention relates to sandals.

The great objection to the ordinary bath- or bed-room sandal is its tendency to drop 15 from the foot of the wearer in walking which necessitates a scuffing or shuffling gait on the part of the wearer to keep the sandal on the foot.

One object of the present invention is to 20 produce a sandal which may be readily slipped on and off the foot but which at the same time will be snugly held on the foot of the wearer and will have no tendency to drop off in walking even though the wearer 25 lifts his foot as in ordinary walking.

Another object of the invention is to produce an improved sole which, although it is particularly applicable to a sandal, may nevertheless be used for a shoe or similar article.

Still another object of the invention is to 30 so combine the straps or flaps which hold the sandal on the foot with the sole that the sandal may be assembled and manufactured very cheaply.

With the above objects in view, the present invention consists in the sandal herein-after described and particularly pointed out in the claims.

In the drawings, Figure 1 is a view, in 40 perspective, of the sandal; and Fig. 2 is a cross section taken through the sole of the sandal just back of the flaps which constitute the upper of the sandal.

Referring to the drawings, the sandal 45 comprises a sole 1, two straps or flaps 2 and 3 which are secured at either side of the ball portion of the sole and are adapted to be brought up over the arch of the foot, and an elastic lacing 4 by which the free ends of 50 the flaps 2 and 3 are laced together over the top of the foot. When the foot is put in the sandal, the lacing 4 yields and holds the flaps 2 and 3 snugly over the top of the foot. When the foot is bent in walking, the lacing 55 4 yields somewhat to the arch of the foot making the sandal more comfortable to wear

in walking, and when the foot is flat in the sandal the elastic lacing 4 causes the flaps 2 and 3 to hug the foot and effectually prevent the sandal from dropping off, so that the 50 wearer may raise his feet in walking with no likelihood of the sandals dropping off. This advantage over the ordinary type of "Chinese" or "Japanese" sandals is obvious and contributes greatly to the comfort of the 55 wearer especially in going up or down stairs. By using an elastic lacing it is possible to make the flaps 2 and 3 of ordinary cloth, thus cheapening the cost of manufacture and at the same time attaining all of the advantages of an elastic upper for the sandal and also making the sandal adjustable for feet of different thicknesses. Moreover since the lacing 4 is the only part of the sandal which 60 contains rubber or like elastic, it may be 65 thrown away and a new lacing substituted whenever the rubber loses its elastic qualities.

In manufacturing the sandal, two pieces 5 and 6 of leather-board are cut in the shape 70 of the outline of the foot. These pieces of leather-board are then coated with an adhesive compound such as cement, and pieces of cloth 7 and 8 are pressed against the faces 75 of the pieces of leather-board and thus cemented thereto. The free edges 9 of the cloth are turned over the edges of the leather-board and laid flat against the opposite faces 80 of the leather-board. The piece of cloth 7, which covers the piece of leather-board 85 which forms the bottom of the completed sandal, is preferably of a piece of wear-resisting canvas, while the piece of cloth, which forms the upper surface next to the foot, is preferably of some softer material. The two 90 cloth covered pieces of leather-board are then laid together with their cloth covered faces exposed. The lower edges 10 and 11 of the flaps 2 and 3 are placed between the edges of the two pieces of leather-board and 95 a line of stitching 12 is sewn through both pieces of leather-board near their edges, thus firmly uniting the two pieces of leather-board and the lower edges of the flaps 2 and 100 3 which lie between them.

The stitching passes through the free edges of the cloth coverings 7 and 8, which are between the pieces of leather-board so that in the completed sandal these free edges of the cloth are tucked in and the neat and attractive appearance of the completed sandal is thereby enhanced. The tucked-over 105 110

edges of the cloth bind the edges of the leather-board and prevent these edges from breaking, and also provide four thicknesses of cloth to support the line of stitching. On account of its weakness the leather-board could not of itself sustain the stitches and it is of advantage to have the stitches pass through as many thicknesses of binding material as possible. The use of the turned-over edges of the cloth coverings of the leather-board allows the sandal to be manufactured much more cheaply than if a separate strip of tape were sewn around to bind the edges of the sole. In this connection it is to be noted that but a single stitching operation is required in making the completed sandal, said stitching operation serving both to unite and bind the edges of the sole portion and also to assemble the upper portion or flaps therewith. After the flaps 2 and 3 have been sewn to the sole, they are turned up and their upper or free edges laced together by the elastic lacing 4 which passes through suitable eyelets 13 in the edges of the flaps. The flaps 2 and 3 consist of fabric which is preferably stiffened somewhat so that they will stand up from the sole to allow the foot to be readily slipped into the sandal. The sandal is very cheap to manufacture, presents an attractive appearance and may be packed in a very small space for shipping.

While the sole is preferably shown as embodied and constituting a part of the sandal, it will nevertheless be evident that the sole may be equally well used in the manufacture of light house shoes or slippers. It is evident that other material, such as pasteboard,

straw-board or leather, may be used in the place of leather-board in making the sandal, and hence the term leather-board, as used in the specification and claims, is intended to define stiffening material possessing the qualities of leather-board.

While a preferred embodiment of the present invention has been illustrated and described, it is nevertheless to be understood that the invention may be embodied in other forms within the scope of the following claims.

1. A sole for a shoe, slipper or the like, having, in combination, two pieces of leather-board cut in the shape of the outline of the foot and united near their edges by a line of stitching, and cloth coverings for the pieces of leather-board, the edges of the cloth being tucked between the opposing faces of the leather-board and held by said line of stitching.

2. A sandal, having, in combination, a sole portion comprising two pieces of leather-board and cloth coverings for said pieces of leather-board, said pieces of leather-board being stitched together by a line of stitching near their edges with the free edges of the cloth coverings tucked between them, and an upper portion comprising two flaps secured between the edges of the leather-board at the sides of the ball portion by said line of stitching and an elastic lacing for lacing together the flaps over the top of the foot.

DANIEL W. CHASE.
